DEVICE PRODUCING ORNAMENTAL BUBBLE
EFFECTS AND METHODAbraham Abramson, New York, N. Y., assignor to
Raylite Electric Corp., Bronx, N. Y., a corpora-
tion of New York

Application February 21, 1946, Serial No. 649,158

14 Claims. (Cl. 240—10)

1

This invention relates to the manufacture of bubble-ornament devices, and more particularly is directed to the constructions of such device and a method of operating same.

Among the objects of the invention is to generally improve devices of the character described and the method of operation thereof which shall comprise few and easily assembled parts, which shall be economical to manufacture and adapted for quantity production so as to provide a cheap and inexpensive product, which shall be dependable and reliable in operation requiring a minimum of external heat supply, and which shall be practical and efficient to a high degree in use.

This invention is a continuation in part to the subject matter covered in applicant's like copending applications filed herewith and applications S. N. 598,569 (Patent No. 2,412,379) and 598,570, filed June 9, 1945 for Decorative illuminated devices and method.

Other objects accordingly consists of features of constructions and method, combinations of elements, arrangement of parts and steps in operation which will be exemplified in the constructions and method hereinafter described and of which the scope of the application will indicate in the following claims.

In the accompanying drawing in which possible illustrative embodiments of the invention are shown.

Fig. 1 is a front elevational view partly broken away to expose the interior, showing a bubble-ornament device constructed to embody the invention.

Fig. 2 is an enlarged fragmentary front elevational view of the device shown in Fig. 1.

Figs. 3 and 3a are cross sectional views taken on lines 3—3 and 3a—3a, respectively, in Fig. 2.

Fig. 4 is a perspective view of the double diaphragm removed from the assembly.

Fig. 5 is a fragmentary front elevational view showing a modified form of the invention constructed with a different diaphragm.

Fig. 6 is a cross sectional view taken on line 6—6 in Fig. 5, and

Fig. 7 is an enlarged fragmentary front elevational view like Fig. 5 showing another modified construction embodying the invention.

Heretofore, ornamental bubbling devices of the character described used for various purposes required a high degree of skill in manufacture and assembly to obtain reliable predetermined desired result and reproductions. In the present invention such devices are made simple in construction and in method of operation, yet oper-

ate with positive assurance to give predetermined desired results with the unfailing reliability and dependability of performance.

To this end, as seen in the drawing there is provided an improved bubble-ornament device 10 constructed to embody the invention which is seen to include a vertically disposed transparent tube body made of glass or other translucent material designated as 11 having an integral closed lower or bottom end 11a, preferably made flat, and a sealed top end 11b. Said body portion 11, when the device 10 is intended to simulate a Christmas tree decoration may be made in appearance, such as outline, form, shape and size to simulate a candle.

In the form of the invention shown in Figs. 1 and 2, the tube body 11 contains a suitable readily volatilizable liquid 12, such as ether, wood alcohol or any others, well known in this art which is translucent, has a low boiling point and preferably is non-flammable for example, methylene chloride, or a mixture of methanol and carbon tetrachloride. The liquid 12 may be placed into the tube body 11 through the upper or top end 11b thereof before fusing the latter for hermetically sealing said liquid 12 therein at a level so as to leave an adequate chamber or space 13 in said tube end 11b. Said sealed space 13 above the liquid 12 may be evacuated to permit lowering the boiling point normally required for the liquid 12. Said space 13 constitutes a condensing and heat dissipating means for liquefaction of bubbles 15 rising in the liquid 12 to the level thereof, as shown in Fig. 2.

There is provided a double diaphragm member 16, formed preferably of a single thin sheet material comprising an upper partition layer 16a and a lower partition layer 16b arranged in parallel spaced apart alignment by a suitable interconnecting portion 16c to provide a separating tube body or space 17 of shallow depth between said layers 16a and 16b. Said diaphragm member 16 is fitted or seated in the lower end of the tube body 11 preferably to position said lower layer 16b short of said tube bottom end 11a so as to leave another space 18 between said lower layer 16b and tube bottom end 11a.

When ether is used as liquid 12, copper or brass is a desirable sheet material to use for the diaphragm 16 as it forms a protective means to eliminate possible explosive derivatives.

For supplying heat to operate device 10 any suitable source may be provided as for example, as shown in Fig. 1, the tube 11 is supported with the lower or bottom end 11a thereof located in

close proximity to lamp bulb 20a of an incandescent lamp 20. The latter, as here shown, is mounted in an electric socket 21 of a Christmas tree lighting outfit (not shown) of any well understood construction by means of a sleeve holder or connector 22 made of fiber, glass, plastic or other non-combustible material. The lower end 22a of sleeve holder 22 may snugly fit over the lamp bulb 20a and upper end 22b of holder 22 snugly fit over the lower or bottom tube end 11a so that the holder 22 provides a relatively firm interconnecting support or rigid coupling between the heat source and the tube body 11. The holder 22 also serves as a conduit to guide the surrounding air heat conducting medium from glowing lamp filament 20b of the lamp bulb 20a to the tube bottom end 11a and said space 13 therein.

In the device 10 as shown in Fig. 1, the diaphragm member 16 is preferably tightly wedged in the position shown at the periphery thereof. Said layers may be provided with angular edge rim or flanges 16d and 16e to increase the gripping effect for retaining said diaphragm member 16 against accident displacement, and as here shown, said double diaphragm member 16 has layers 16a and 16b thereof perforated with spaced openings 16f and 16g, respectively. When said device 10 is operating the liquid column 12 above the diaphragm member 16 communicates with vapors 19 in separating section 17 between said layers 16a and 16b, and a small quantity of liquid 12a in space 18 below the lower partition layer 16b, permits formation of bubbles 15 to pass through upper layer openings 16f as hereinafter described.

In practising the invention, assuming the socket 21 is positioned on a Christmas tree (not shown) or arranged for other decorative display purposes and connected in an electric circuit power supply (not shown) for lighting the lamp 20 in the well understood manner, heat and light radiated from the lamp filament 20b is effective to vaporize liquid 12a in the tube bottom space 18 below the lower layer 16b and to maintain separating section 17 between said layers substantially filled with bubbleless vapor 19.

The heat from lamp filament 20b beside producing said vaporization also causes "flash" expulsion of a portion of the confined vapors 19 to expand through said partition layer opening 16f into the liquid column 12 thereabove in the form of a stream of flowing bubbles 15, rising through the liquid column 12. The sleeve holder 22 serves as a conduit to confine the heat conducting medium, namely, air therein for producing the necessary degree of heat and requiring a minimum heat source at lamp filament 20b, sufficient light beams from the latter being projected through said diaphragm openings 16f and 16g to illuminate the liquid column 12 and bubbles 15 to produce an attractive activated bubble lighting effect.

The lighting of bulb 20 also illuminates the side walls of the tube body 11 to the top end 11b thereof and imparts an appearance suggestive of a lighted candle.

It has been found that an absolutely tight joint between the diaphragm layer flange 16d and the side walls of the tube body 11 is not required and that a slight leakage thereat does not seriously affect the operation of the device 10.

The improved method embodying the invention in the form above described will now be apparent. The column of volatile liquid 12 within the tube body 11, which when said device 10 is operating,

extends between the upper diaphragm layer 16a and the top tube space 13, and is under less than atmospheric pressure because of the evacuated condition of said top space 13. The device 10 has 5 external illuminating radiant heat applied, as by means of a suitable heat source, such as the glowing filament 20b of lamp 20 which is directed to maintain said space 17 substantially filled with vapor 19. Heat from said lamp filament 20b is 10 then continuously supplied to the vapors 19 in said separating section 17 to an effective degree sufficient through heating of liquid 12a in space 18 for generating pressure periodically in excess of that due to the column of liquid 12 whereby 15 "flash" expulsion of a portion of the vapors 19 takes place expanding through diaphragm layer opening 16f and forming a bubble 15 which floats up through the liquid column 12. After each 20 "flash" expulsion the pressure of vapors 19 for an instance apparently is reduced to permit a small amount of liquid 12 to trickle down below the diaphragm member 16 where it is vaporized. The vapor pressure in said separating section 17 25 between said diaphragm layers 16a and 16b is then again built up and said "flash" expulsion repeatedly forming other bubbles 15 in passing through said diaphragm opening 16f in succession.

Thus a stream of flowing bubbles 15 rising 30 through liquid column 12 is produced and is illuminated by light beams emanating from the lamp filament 20b.

The bubbles 15 of the flowing stream on reaching top space 13 after passing through the liquid 35 column 12 are cooler, condense and liquify returning to the liquid column 12 in tube body 11 and replenishing same to continue the cycle of operation above described as long as said illuminating radiant heat from lamp filament 20b is 40 directed to act on said vapors 19 in separating section 17. To be more accurate said bubble forming action continues to take place as long as there exists a heat gradient or differential temperature between the hotter portion of said vapors 45 19 forming bubbles 15 and the cooler evacuated tube top space 13.

In Fig. 5 there is shown a modified form of the invention having a double diaphragm member 26 having upper partition 26a and lower partition 50 26b which differs from said diaphragm member 16 above described by providing in place of opening 16f in upper partition layer 16a, one or more peripheral through-passages or grooves 26f between rim edge or flange 26d on partition 26a and the side walls of tube body 11 as shown in Fig. 3. The method of operation is the same as has been described with the construction assembly using diaphragm 16 and shown in Fig. 1 except "flash" expulsion of vapors 29 in space 27 forming the bubbles 15 takes place through one of said 55 60 65 70 75 80 85 90 95 100 105 110 115 120 125 130 135 140 145 150 155 160 165 170 175 180 185 190 195 200 205 210 215 220 225 230 235 240 245 250 255 260 265 270 40 within said space 38, as shown in Fig. 4a. The form of the invention shown in Fig. 4, operates in the same manner as has been described for device 10 and shown in Fig. 1, the "flash" expulsion of vapor 39 in space 37 forming bubbles 15 takes place through said layer openings 36f, of the lower partition layer 36b.

In the form of the invention shown in Figs. 2, 5 and 7, the through-openings or passages in upper diaphragm layers, 16f, 26f and 36f, respectively, may be made larger than the through-openings 16g, 26g and 36g in lower diaphragm layer, respectively.

It is to be understood that all the modified constructions described above may be assembled in holders 22 and supportingly mounted over incandescent lamps 20 in the manner described for device 10 and shown in Fig. 1.

It is therefore seen that there is provided improved devices and a method of operation in which the objects of the invention are achieved and which are well adapted to meet all conditions of practical use.

As various possible embodiments may be made in the above invention for use for different purposes and as various changes might be made in the embodiments and method above set forth, it is understood that all the above matters here set forth, or shown in the accompanying drawing are to be interpreted as illustrative and not in a limiting sense.

Thus having described my invention, I claim as new and desire to secure by Letters Patent:

1. In a device of the character described producing ornamental bubble effects, a vertically disposed sealed transparent tube body, a translucent low-temperature boiling liquid column filling a mid-portion of said tube body, thin sheet material spaced apart upper and lower diaphragm layers positioned in the lower end of said tube body with said lower diaphragm layers short of the bottom thereof to provide space for a relatively small quantity of liquid from said column, heated bubble-free vapors of said liquid column substantially filling the tube body between said diaphragm layers for retaining the liquid column above the upper layers diaphragm and said quantity of liquid below the lower diaphragm, and means carried by said diaphragm layers communicating said vapors with the liquid column and said quantity of liquid, above and below said diaphragm layers respectively, to permit "flash" expulsion of expanding portions of said vapors as bubbles into the liquid column through the upper diaphragm layers and to permit seepage from the liquid column through said vapors and into said space to replenish the quantity of liquid therein.

2. In a device of the character described producing ornamental bubble effects, a vertically disposed sealed transparent tube body, a translucent low-temperature boiling liquid column filling a mid-portion of said tube body, thin sheet material spaced apart upper and lower diaphragm layers positioned in the lower end of said tube body with said lower diaphragm layer short of the bottom thereof to provide space for a relatively small quantity of liquid from said column, heated vapors of said liquid column substantially occupying the tube body between said diaphragm layers at a pressure to retain the liquid column above said upper diaphragm layer and said quantity of liquid below the lower diaphragm layer, means carried by said diaphragm layers communicating said vapors with the liquid column and said quantity of liquid, above and below said diaphragm layers re-

spectively, to permit "flash" expulsion of expanding portions of said vapors as bubbles into the liquid column through the upper diaphragm layer and to permit seepage from the liquid column through said vapors and into said space to replenish the quantity of liquid therein, said communicating means including through-opening in each of said diaphragms, and means for retaining said diaphragm layers in said position against accidental movement.

3. A device as defined in claim 1 in which said communicating means includes at least one passage between said upper diaphragm and the adjacent wall of the tube body through which said expanding portions of the vapors pass as bubbles.

4. In a device of the character described producing ornamental bubble effects, a vertically disposed sealed transparent tube body, a translucent low-temperature boiling liquid column partially filling said tube body, thin sheet material spaced apart upper and lower diaphragm layers positioned in the lower end of said tube body and providing a section space under the lower diaphragm layer, heated bubble-free vapors of said liquid column expanded to provide a pocket between said diaphragm layers with the liquid column retained above said upper diaphragm and a relatively small quantity of heated liquid from said column occupying said section space under the lower diaphragm layer, said diaphragm layers each having an opening therethrough communicating said vapors with the liquid column to permit "flash" expulsion of expanding portions of said vapor as bubbles up through the upper diaphragm layer opening into the liquid column and to permit vaporization passage of portions of said quantity of heated liquid in the section space through the lower diaphragm layer opening into the space vapor pocket, said tube body formed with a heat dissipating upper end above the level of said liquid column to which the bubbles rising in said column pass for liquefaction, and heating means direct to said quantity liquid in said section space.

5. A device as defined in claim 4 in which said upper diaphragm layer opening is made larger than the lower diaphragm layer opening.

6. A device as defined in claim 4 in which said section space is filled with a porous granular material.

7. A device as defined in claim 4 in which said upper diaphragm layer opening comprises a passage between said upper diaphragm layer and adjacent wall of the tube body.

8. In a device of the character described producing ornamental bubble effects, a vertically disposed tube body having a lower end, a liquid sealed in to partially fill said tube body, and thin sheet foraminous material spaced apart upper and lower diaphragm layers positioned in the lower end of said tube body to provide a pocket between said diaphragm layers and a section space below said lower diaphragm.

9. A device as defined in claim 8 in which said diaphragm layers are formed with integral means for retaining said diaphragm layers in said position.

10. A device as defined in claim 8 in which said diaphragm layers are formed with means for retaining same against movement from said spaced apart position, and porous material confined in said section space under the lower diaphragm layer.

11. A device as defined in claim 4 which includes 75 interconnecting means for supporting and retain-

7
ing said diaphragm layers in said spaced apart position.

12. In a device of the character described producing ornamental bubble effects, a vertically disposed tube body having a lower end, a liquid sealed in to partially fill said tube body, and thin sheet material spaced apart upper and lower diaphragm layers positioned in the lower end of said tube body to provide a pocket between said diaphragm layers and a section space below said lower diaphragm, said layers each having communicating passages therethrough to the opposite side thereof.

13. In a method of the character described for producing ornamental bubble effects, the steps of forming a first bubble-free vapor pocket of predetermined constant volume under pressure of a column of liquid and over a communicating second pocket of predetermined volume containing a relatively small quantity of liquid, and heating said first vapor pocket by passing vapors therethrough from heated liquid in said second pocket

8
thereunder for intermittently "flash" expulsion of an expanded portion of the vapor from said first vapor pocket as a stream of bubbles flowing solely up through the liquid column.

14. The method as defined in claim 13 in which seepage from the liquid column drains through the first vapor pocket into said communicating pocket to replace the expanded vapor portion forming said bubble stream.

10
ABRAHAM ABRAMSON.
